UNITED STATES PATENT OFFICE.

RICHARD E. JONES, OF HAGERSTOWN, MARYLAND, ASSIGNOR TO VICTOR COOLER DOOR COMPANY, INC., OF HAGERSTOWN, MARYLAND, A CORPORATION OF MARYLAND.

FASTENER.

Application filed March 8, 1927. Serial No. 173,770.

My invention relates to new and useful improvements in fasteners and more particularly to such a device primarily intended for use in connection with refrigerators and 5 cold storage room doors, the principal object of the invention residing in the provision of a fastener which may be operated from either side of the door for unlocking and which is automatically fastened by spring 10 pressure upon closure of the door.

Another object of the invention resides in the provision of a housing which is adapted to be connected to one face of the door, the housing carrying the pivoted latch and one 15 of the operating levers, the spring for normally holding the latch in fastening position being enclosed within the housing.

A further object consists in providing means for fastening the latch in its fastening 20 position, a projection being formed on the latch and extending through an opening in the housing for receiving a locking member.

With the above and other objects in view, which will appear as the description proceeds, my invention consists in the novel details of construction and arrangements of parts, described in the following specification and illustrated in the accompanying drawings, and while I have illustrated and 30 described the preferred embodiments of the invention, as they now appear to me, it will be understood that such changes may be made as will fall within the scope of the appended claim.

In the drawings:

Fig. 1 is a face view showing the fastener connected to a door.

Fig. 2 is a rear face view of the fastener.

Fig. 3 is a section on line 3—3 of Fig. 40 1; and

Fig. 4 is a section on the line 4—4 of Fig. 1.

In the drawings 1 indicates a door and 2 the door frame.

My improved form of fastener consists of the housing 3 which is adapted to be secured to the face of the door by means of the screws 4 or other suitable fastenings. A latch 5 extends longitudinally within the 50 housing 3 and is pivotally connected thereto at 6, a roller 7 being mounted adjacent the outer free end of the latch for engagement with the keeper 8 which is secured to the door frame 2 by means of the bolts 9 and nuts 10 as shown more particularly in Fig.

1 of the drawings. The keeper is provided adjacent each end, with an elongated opening 11 through which the bolts 9 will extend. By this construction the keeper may be vertically adjusted upon the door frame. 60 The latch 5 is provided, intermediate its ends, with the elongated opening 12 into which extends the projection 13 formed on the lower end of the lever 14 pivotally connected to the housing 3 at 15. The lever 65 14 is formed, intermediate its ends, with an elongated opening 16 into which extends a pin 17 by means of which the lever 14 is connected to the forked end 18 of the rod 19. The rod 19, as shown 70 more particularly in Fig. 3 of the drawings, extends through the housing 3, the door 1, and the plate 20. The plate 20 is secured to that face of the door 1, opposite to that to which the housing is secured, by 75 means of the screws 21 or other suitable fastenings and is provided with the lugs or projections 22 to which the lever 23 is pivotally connected at 24. The end of the rod 19, which extends through the plate 20, is 80 threaded as shown at 25 to receive the internally threaded member 26 having the outwardly extending spaced horizontal arms 27 between which the lever 23 extends. The lever 23 is formed intermediate its ends with 85 the elongated opening 28 through which a pin 29 carried by the arms 27 extends.

A vertically extending pin or projection 30 is formed on or secured to the latch 5, as shown more particularly in Fig. 4 of the 90 drawings, and passes through an opening 31 formed in the top of the housing 3. A coiled spring 32 surrounds the pin 30 between the inner wall of the housing and the top of the latch and normally holds the latch 95 in its lowered or closing position. A removable plate 33 is secured to the inner face of the housing 3 by means of a screw 34 or other suitable fastening and the latch 5 operates between this plate and the outer face of 100 the housing. The plate 33 is positioned at a point adjacent the pin 30 and its surrounding spring 32 so that when the plate is removed access may be gained to the spring and the removal of the latch 5 from the 105 housing may be facilitated.

Formed on or secured to the lower edge of the latch 5, intermediate the ends thereof, is the downwardly projecting pin 35 which is adapted to pass through an opening 36 110

formed in the lower wall of the housing 3. The pin 35 will be provided with a transversely extending opening to receive the shackle of a lock 37.

5 From the above detailed description it is thought that the construction and operation will be understood. It will be noted that I have provided a fastener in which there are relatively few parts, which may be readily 10 attached to or detached from the face of the door, which may be operated from either side of the door, and which may be automatically locked by spring pressure when the door is closed. When the door is closed 15 the spring 32 forces the latch downwardly into proper engagement with the keeper 8 to hold the door in fastened or closed position. When the fastener 37 is connected to the pin 35 the latch is held against vertical movement and therefore the fastener 20 cannot be unfastened. The housing 3 is preferably connected to the outer face of the door and to operate the latch from the outer face of the door the lever 14 is manipulated 25 so that the projection 13 thereof will raise the latch 5 and release the same from the keeper 8. From the inside of the door the latch is raised by manipulation of the lever 23. The lever 23 will slide the rod 19 and in turn operate the lever 14 to raise the 30 latch 5. When the housing 3 is detached from the door the latch 5, the lever 14, and the rod 19, with their associated parts, may be removed as a unit, it being understood

35 that the internally threaded member 26 will be disconnected from the rod 19 so that the same may be withdrawn through the door. The removable plate 33 cooperates with the housing 3 to form a guide for the latch 5 and at the same time allows for access to the 40 spring 32 and facilitates the removal of the latch from the housing when desired.

Having fully described my invention what I claim as new and desire to secure by Letters Patent is:

45 A fastener of the character described adapted to be connected to or removed from a door or the like as a unitary structure including a housing having a longitudinally extending recess forming an open back, 50 a latch pivotally connected to the housing and extending longitudinally thereof in the recess, a pin carried by the latch and extending through the top of the housing, a spring surrounding the pin between the top of the housing and top of the latch, 55 said pin and spring being located behind the front face of the housing and within the recess, a plate detachably connected to the housing and extending over the open back 60 of the housing to form the guide for the latch, a projection formed on the outer face of the housing, and a lever pivotally connected to the projection and engageable with the latch for operating the same.

65 In testimony whereof I hereunto affix my signature.

RICHARD E. JONES.
